(57) **CLAIM**

(21) Appl. No.: **29/315,910**

The ornamental design for an attachment portion of a cladding tile, as shown and described.

(22) Filed: **Aug. 4, 2009**

DESCRIPTION

(30) **Foreign Application Priority Data**

FIG. 1 is a front perspective view of one embodiment of an attachment portion of a cladding tile showing my new design; FIG. 2 is a rear perspective view of the attachment portion of a cladding tile shown in FIG. 1;

FIG. 3 is a front view of the attachment portion of a cladding tile shown in FIG. 1;

FIG. 4 is a rear view of the attachment portion of a cladding tile shown in FIG. 1;

FIG. 5 is a top view of the attachment portion of a cladding tile shown in FIG. 1;

FIG. 6 is a bottom view of the attachment portion of a cladding tile shown in FIG. 1;

FIG. 7 is a left side view of the attachment portion of a cladding tile shown in FIG. 1; and,

FIG. 8 is a right side view of the attachment portion of a cladding tile shown in FIG. 1.

The broken lines are for illustrative purposes only and form no part of the claimed design.
